UNITED STATES PATENT OFFICE.

JAMES R. DAKE, OF MERRILL, WISCONSIN, ASSIGNOR OF ONE-HALF TO
ROMUALD A. OLESHAK, OF SAME PLACE.

MACHINE FOR COLLECTING PRECIOUS METALS FROM RIVER-BEDS.

SPECIFICATION forming part of Letters Patent No. 664,626, dated December 25, 1900.

Application filed June 20, 1900. Serial No. 20,986. (No model.)

To all whom it may concern:

Be it known that I, JAMES R. DAKE, a citizen of the United States, and a resident of Merrill, in the county of Lincoln and State 5 of Wisconsin, have invented a new and Improved Machine for Collecting Precious Metals from River-Beds, of which the following is a full, clear, and exact description.

This invention relates to machines for recovering gold or the like from the sand of river or other water beds; and the object is to provide a machine of this character of simple construction, comparatively inexpensive, portable, and that may operate by current pressure equally well in either deep or shallow water.

I will describe a machine for collecting precious metals from river-beds embodying my invention and then point out the novel features in the appended claims.

Reference is to be had to the accompanying drawings, forming a part of this specification, in which similar characters of reference indicate corresponding parts in all the figures.

Figure 1 is a side elevation of a machine embodying my invention. Fig. 2 is a sectional elevation thereof. Fig. 3 is a section on the line 3 3 of Fig. 2. Fig. 4 is a detail showing the blade-stop employed, and Figs. 5, 6, 30 and 7 are details showing a means that may be employed for causing swinging motions of the sluice.

The machine comprises a frame consisting of side uprights 10 11, connected at the forward ends by a cross-bar 12 and at the rear ends, near the bottom, by a cross - bar 13, which also serves as a bumping-block for the sluice, as will be hereinafter described. The frame is further braced by metal rods 14 and 40 15. Having bearings in the sides of the frame is a shaft 16, to the outer ends of which power-wheels 17 are attached. Each wheel is provided with a series of blades 18, the blades being pivotally connected to the spokes of the wheels, so as to swing outward when the current strikes them and to swing inward against the wheels when relieved of pressure or moving against the current. The blades are limited in their outward movement by 45 means of stop-lugs 19, attached to the blades and adapted to engage with the spokes or

with lateral projections thereon, as indicated in Fig. 1, and also in Fig. 4. While I prefer to show two power-wheels, as indicated in the drawings, it is obvious that a single wheel 55 may be employed. By using two wheels, however, the machine is more evenly balanced.

Attached to the shaft 16, between the side pieces of the frame, is a sprocket-wheel 20, 60 around which a sprocket chain or carrier 21 extends. Forward of the frame the said chain engages with a sprocket-wheel 22, supported by arms 23, attached to the outer end of a guide-board 24, over which the upper 65 stretch of the chain moves, as indicated. This guide-board 24 at its inner or rear end has swinging connection with the shaft 16 by means of arms 25, attached to said board and engaging with the shaft. At suitable intervals on the carrier or chain 21 buckets 26 are mounted. These buckets are open at one end and are adapted to scoop up the sand from the bed of a river and carry the same to a sluice 27, extended rearward from the 75 frame and having swinging connection with said frame. This sluice is open at its ends, but closed at all its sides, and on its lower wall riffles 28 are transversely arranged. These riffles form pockets in which the gold 80 will be deposited during the operation of the machine.

Extended forward of the power-wheels and half-way up their circumference are deflector - plates 29, which prevent the current 85 from engaging with the blades of the wheels at the lower portion, but permit the current to engage with the series of blades that may be uppermost, and arranged above each wheel is a curved plate 30, which will have a tendency to force the water downward to compress it upon the wheels.

Attached to standards 31, extended upward from the machine-frame, is an air-chest 32, which is designed to hold the machine in upright position. As in many currents of water the air - chest, if comparatively full of air, might have a tendency to raise the machine, in such event a certain amount of water may be placed in the chest to give sufficient weight 100 to hold the machine upon the water-bed.

In connection with the machine I employ a

float 33. This float may be of the catamaran order, or it may consist of rafts of logs. As a means for raising and lowering the machine a rope 34 is attached at one end to rods 35, 5 connected to the machine, and is then carried upward over a pulley 36, supported by a frame 37, mounted on the float, and then under a windlass 38 on the float. From a windlass 39 on the float a rope 40 extends around a block attached to an anchor 41 and then to a connection with rods 42, extended forward from the frame of the machine. The anchor 41 is designed to prevent the machine from being moved with the current, and it is obvious 10 that by operating the windlass 39 the machine may be moved forward when desired. The anchor 41 also holds the float from movement in one direction, while an anchor on a rope or cable 43 at the opposite end will prevent 15 the float from moving in the other direction, and it is also designed to hold the float when the windlass is operated to move the machine. From the sluice 27 a rope 44 extends upward and connects with a slip-clutch 20 windlass 45 on the float, and a rope or cable 46 extends from the guide-board 24 to a windlass 47 on the float. By means of this windlass and its connection with the guide-board the carrier may be raised or lowered, as desired, 25 to accommodate it to the bottom of the stream.

Under ordinary circumstances the machine will be operated by the water-current against the blades of the wheels; but should the machine become clogged by any substance carried into it by the conveyer I provide means to ascertain such fact, or whether the machine is at a standstill. This means comprises a wire 48, attached at its lower end to the board 30 24 and extending upward to the float, where it terminates in receivers 49, which may consist of thin metal diaphragms arranged in suitable casings similar to a mechanical telephone - receiver. For convenience the wire 48 may be fastened to the rope or cable 46.

In operation the machine may be raised and lowered by means of the windlass 38. When the machine is in the desired position and anchored, the water-current will rotate 35 the power-wheels, and consequently set the bucket-carrier in operation. The buckets 26 will scoop up the sand containing gold or other metal and deposit the same into the sluice 27, and the water flowing through this sluice will carry the sand and gold, the sand being discharged at the outer end of the sluice, while the gold will settle in the pockets at the bottom of the sluice. If desired, quicksilver may be placed in the pockets. 40 The settling of gold from the sand and water will be accelerated by imparting an up-and-down movement to the sluice and causing it to bump upon the cross-bar 13. This movement may be caused by operating the slip-clutch windlass 45. To partially cut off the current-pressure from the discharge end of the carrier, rearwardly-extending divergent

deflector-plates 30^a are attached to the cross-bar 12.

While I do not claim in broad form a slip-clutch for the windlass 45, I show a practical mechanism in Figs. 5, 6, and 7. The windlass is provided at one end with a ratchet 50, designed to be engaged by a clutch or pawl 51, mounted on a disk 52, rigidly connected 70 to the shaft upon which the windlass is loosely mounted. As the shaft is rotated by manual or other power, when the clutch is in engagement with the ratchet the windlass will be rotated in such manner as to raise 75 the sluice. The clutch will be held in such engagement with the ratchet by means of a spring 53 engaging at one end with the disk and at the other end with an extension 54 of the clutch or pawl. This extension 54 is 80 curved, and when it comes in contact with any one of a series of fixed pins 55, attached to the frame of the windlass, the clutch will be rotated out of engagement with the ratchet, thus permitting the windlass to rotate in 85 the opposite direction as the sluice is moved downward by its weight. Of course after leaving its engagement with a pin 55 the clutch will be again thrown into engagement 90 with the ratchet-wheel.

Having thus described my invention, I claim as new and desire to secure by Letters Patent—

1. A machine for collecting precious metals from water-beds, comprising a frame, a shaft 100 mounted in said frame, a current-pressure wheel attached to the said shaft, the said wheel having laterally-swinging blades and adapted to be entirely submerged, an endless carrier operated from said shaft, buckets on 105 said carrier, and a sluice into which the buckets discharge, substantially as specified.

2. In a machine of the character described, a frame, an endless carrier arranged in said frame, a current-operated wheel for moving 110 said carrier, buckets on the carrier, a compression-plate above the wheel, a sluice into which said buckets discharge, and riffles on the bottom wall of said sluice, substantially as specified.

3. In a machine of the character described, a frame, an air-chest rigidly attached to said frame, a shaft mounted in the frame, power-wheels attached to said shaft, an endless carrier operated from the shaft, buckets on said carrier, and a sluice mounted in the frame and into which the buckets discharge, substantially as specified.

4. In a machine of the character described, a frame, current-operated wheels mounted on a shaft having bearings in said frame, an endless carrier operated from said shaft, deflector-plates extended forward of the forward sides of the wheels, a compression-plate above each wheel, a sluice into which the carrier 120 discharges, and means for imparting a vertical movement to said sluice, substantially as specified.

5. In a machine of the character described,

- a frame, current-operated wheels mounted on a shaft having bearings in said frame, an endless carrier operated from said shaft, deflector-plates extended forward of the forward 5 sides of the wheels, a compression-plate above each wheel, and a sluice into which the carrier discharges, substantially as specified.
6. In a machine of the character described, a frame, an endless carrier arranged in said 10 frame, a current-operated wheel for moving said carrier, a compression-plate above the wheel, buckets on the carrier, and a sluice into which said buckets discharge, substantially as specified.
- 15 7. In a machine for collecting gold from water-beds, a frame, a float, means for anchoring the frame and float, an air-chamber rigidly connected to the frame, a shaft mount-
- ed in the frame, a current-operated wheel mounted on said shaft, a sprocket-wheel on the shaft, a guide-board having swinging connection with the shaft, a sprocket-wheel carried at the outer end of said guide-board, a sprocket-chain extended around the two sprocket-wheels, buckets on said chain, means 20 for raising and lowering the guide-board, a swinging sluice into which the buckets discharge, and means for continuously swinging said sluice, substantially as specified.
- In testimony whereof I have signed my 25 name to this specification in the presence of two subscribing witnesses.

JAMES R. DAKE.
